UNITED STATES PATENT OFFICE.

GEORGE F. MILLER, OF BROOKLYN, NEW YORK, ASSIGNOR TO AMERICAN CAN COMPANY, OF NEW YORK, N. Y., A CORPORATION OF NEW JERSEY.

SHEET-METAL TYPE-RIBBON SPOOL OR HOLDER.

No. 857,818.

Specification of Letters Patent.

Patented June 25, 1907.

Application filed March 18, 1907. Serial No. 362,849.

To all whom it may concern:

Be it known that I, GEORGE F. MILLER, a citizen of the United States, residing in Brooklyn, in the county of Kings and State of New York, have invented a new and useful Improvement in Sheet-Metal Type-Ribbon Spools or Holders, of which the following is a specification.

My invention relates to improvements in sheet metal spools or holders for type ribbons of type writers or other machines.

The object of my invention is to provide a sheet metal type ribbon spool or holder of a strong, simple, efficient and durable construction, composed of few parts and capable of being rapidly and cheaply manufactured.

My invention consists in the novel construction of parts and devices, and in the novel combinations of parts and devices herein shown and described and more particularly specified in the claims.

In the accompanying drawing forming a part of this specification, Figure 1 is a plan view of a sheet metal type ribbon spool or holder embodying my invention. Fig. 2 is a side elevation. Fig. 3 is a section on line 3—3 of Fig. 1 and Fig. 4 is a cross section on line 4—4 of Fig. 2.

In the drawing, A A represent the sheet metal side plates or disks of the spool, B the core around which the type ribbon C is wound and D the connecting eyelet or thimble.

The side disks or plates A A of the spools are furnished on their inner faces with annular grooves or channels a to receive the circular ends b of the cylindric core B. The side disks A A are provided with central holes a¹ to receive the connecting eyelet or thimble D and with holes a² to receive a stud or pin to cause the spool to turn with the winding shaft in winding the ribbon upon the spool. The disks A are also furnished at their periphery with outwardly turned curls or curved edges a³ to strengthen and stiffen the same and give a smooth finish.

The core B is of cylindrical or tubular

shape and has a butt joint b³ uniting its meeting edges, and is provided with an integral loop b¹ through which the end of the type ribbon C is inserted and an integral tooth b² adapted to be inserted through the end of the ribbon C to hold the same. The connecting eyelet D is a cylindrical or tubular thimble inserted through the holes a¹ in the side disks A of the spool and upset or clenched down to securely clamp the cylindric sheet metal core B between the side disks A A and firmly and rigidly unite all the parts together, while at the same time affording a smooth bearing for the shaft F of the typewriter or other machine upon which the spool turns.

By my improved construction of sheet metal spool, the hollow cylindric core fitting between the disks serves as a brace or strut member, while the hollow or cylindric connecting thimble or eyelet serves as the tension member to clamp and tie all the parts together.

I claim:

1. In a sheet metal spool, the combination with the side disks having circular grooves to receive the ends of a hollow core, a hollow sheet metal core fitting between the side disks and provided with a ribbon retaining loop and tooth, and a central connecting thimble extending through and between the disks and rigidly connecting the disks and core, substantially as specified.

2. The sheet metal type ribbon spool consisting in the side disks having integral channels or grooves to receive the ends of the core, a hollow core fitting between the side disks and a connecting eyelet or thimble extending through and between the disks and clamping the core between them, said connecting eyelet being of less diameter than and separated from the hollow core substantially as specified.

GEORGE F. MILLER.
